UNITED STATES PATENT OFFICE.

ANTHONY J. PFOHL, OF LOCKLAND, OHIO, ASSIGNOR TO PHILIP CAREY MANUFACTURING COMPANY, A CORPORATION OF OHIO.

SPLICING-MACHINE.

1,261,055.

Specification of Letters Patent.

Patented Apr. 2, 1918.

Application filed October 6, 1916. Serial No. 124,049.

To all whom it may concern:

Be it known that I, ANTHONY J. PFOHL, a citizen of the United States, and a resident of and whose post-office address is Lockland, 5 Hamilton county, State of Ohio, have invented certain new and useful Improvements in Splicing-Machines, of which the following is a specification.

My invention relates to splicing machines, 10 and is especially adapted for use in splicing the ends of felt or similar material used in the manufacture of prepared roofing. My invention is, of course, adapted to be used for splicing any other material together.

15 In the drawings, Figure 1 is a side view of my invention; Fig. 2 is an end view; and Fig. 3 is a top view of Fig. 1. In the drawings, 1, 1 are rolls of felt suitably mounted on rolls 24 supported on shaft 25 on bracket 26 projecting from vertical standard 27. A is a frame or table supporting my splicing apparatus. 2 is a roller loosely mounted in bearings in blocks 14 over which the felt 1 passes. 3 is a roller loosely mounted in bearings in the blocks 15 under which the belt passes. 4, 4 are dies adapted to be heated and to be brought together so as to compress between them the 20 spliced joint. 16, 16 are frames mounted on the support or table A through which the shaft 19 passes. Fixedly secured on this shaft 19 are eccentric cams 5, 5 which are so arranged that rotation of the shaft 12 by 25 the lever 6 tends to force the links 20, 27 down carrying with it the upper die 4 so as to compress same against the lower die. The dies 4, 4 are, as shown, steam-heated, although they may be heated by any suitable 30 means.

In the drawings, 9 is a pipe from any suitable steam supply leading to the upper die and 10 is a pipe leading from the far end of the upper die, as shown in Fig. 1, to 35 the near end of the lower die, as shown more clearly in Fig. 3. 11 is a pipe leading from the lower die to permit the same to pass out therefrom.

Mounted upon the frame A are located 40 blocks 17, 17 through which passes the shaft 23 adapted to be operated by the lever 13. Upon this shaft 23 are located eccentric cams 8, one near each end of the shaft and adapted, when the shaft 23 is rotated by the 45 lever 13, to carry the link 22 upward or

downward depending upon the direction of rotation of the shaft so as to move the rollers 7, 7 which are rotatably mounted in the vertically movable blocks 28, 28, toward or away from each other. By rotating the 60 lever 13 clockwise the eccentric cam 8 carries the link 22 downward so as to force the upper roller 7 against the lower roller 7, thus compressing the felt 1 between them and locking it in position.

The end of the felt from the lower roller having been reached, the lever 13 is operated so as to move the eccentric 8 to carry the link 22 down, forcing the two rollers 7, 7, together, thereby locking the felt 70 against movement. As a reserve feed apparatus is used in connection with my splicer where it is desirable to have a constant and uniform feed of the felt, the reserve feed allows for the continuous feed 75 while the splicing operation is being carried on. The end of the felt having been treated with an adhesive, or any other material so as to make the splice, the end of the felt from the upper roller is applied to 80 it and the joint is allowed to pass between the two dies 4, 4 by permitting the locking rollers 7, 7 to operate so as to permit the spliced joint to come in proper position between the dies 4, 4, when the locking rollers 85 7, 7 are again brought together. Then the lever 6 is operated, causing the eccentrics 5, 5 to operate the links 27, 20 so as to move the upper die down against the lower die, thereby compressing the spliced joint under 90 heat so as to thoroughly dry the adhesive.

Having described my invention, what I claim as new and desire to secure by Letters Patent is:

1. In a splicing apparatus, dies, means for heating said dies, means whereby one of said dies can be moved toward the other, means for moving said die and locking means to engage one portion of the material during the splicing operation.

2. In a splicing apparatus, dies, means for heating said dies, means whereby one of said dies can be moved toward the other, means for moving said die, locking means to engage one portion of the material during 105 the splicing operation comprising two rolls, one movable toward the other, and means for moving same.

3. In a splicing apparatus, dies, means for heating said dies, an eccentric whereby one 110

of said dies can be moved toward the other, means for moving said die, locking means to engage one portion of the material during the splicing operation comprising two rolls, one movable toward the other, and means for moving the same.

4. In a splicing apparatus, dies, means for heating said dies, means whereby one of said dies can be moved toward the other, means

for moving said die, means for supporting 10 a roll of material, a tension device for said roll and locking means to engage one portion of the material during the splicing operation.

In testimony whereof, I have signed my 15 name to this specification.

ANTHONY J. PFOHL.
